INVENTOR.

E. M. ROCHA
BY *Victor J. Evans*
ATTORNEY.

UNITED STATES PATENT OFFICE.

EZEKIEL M. ROCHA, OF TULARE, CALIFORNIA.

ROBBER TRAP.

Application filed May 16, 1927. Serial No. 191,896.

This invention relates to improvements in robber traps and has particular reference to a trap for use in banks and like places.

The principal object of this invention is 5 to provide means whereby a robber attempting to hold up a bank or other like institutions may be deposited through an opening in the floor into a receptacle and automatically locked therein.

10 A further object is to provide means whereby a device of this character may be installed in the ordinary building without materially altering the construction of the same.

15 A still further object is to provide a device of this character which is economical to install and one which is not unsightly.

Other objects and advantages will be apparent during the course of the following 20 description.

In the accompanying drawing forming a part of this specification and in which like numerals are employed to designate like parts throughout the same,

25 Figure 1 is a vertical cross section of my device as the same would appear installed in front of a bank window, and.

Figure 2 is a vertical cross section of Figure 1.

30 It often occurs that robbers will hold up the employees of a bank by appearing at the window assuming a position of an ordinary bank customer.

Applicant has therefore provided means 35 whereby the bank employee may operate a hidden electrical contact with a result that the floor adjacent the window will open and the robber will be deposited into a shoot and thence into a receptacle having a hinged cover which will automatically close, as soon 40 as the robber is deposited in this receptacle.

In the accompanying drawing wherein 45 for the purpose of illustration is shown a preferred embodiment of my invention, the numeral 5 designates a trap door positioned in the floor 6 of a building and preferably in front of the customary teller's windows which are indicated at 7 and 8. The trap 5 is hinged as at 9 and is normally maintained on the level with the floor 6 by means 50 of latches 11. These latches are electrically operated as will be later described.

Positioned beneath the floor 6 and surrounding the opening in which the trap is pivoted is a funnel shaped member 12. This 55 funnel shaped member terminates in a

downwardly extending pipe like portion 13 beneath which is placed a receptacle 14 having a cover 16 which is hinged as at 17. A catch is shown at 18 which catch will automatically maintain the cover 16 in closed position as shown in dotted lines of Figure 1, except when released from a point outside of the receptacle 14.

The receptacle 14 is maintained in alignment with the pipe 13 as by a vertically movable ring 19. The movement of this ring is indicated on dotted lines of Figure 2. A latch is shown at 21, which is pivoted in such a manner as to normally maintain the cover 16 in the full line position of Figure 1. A magnet is shown at 22, which magnet is adapted to operate the latch 21 as will be hereinafter described.

Positioned in the bottom of the receptacle 14 is a platform 23 which is normally maintained in an elevated position as by a spring 24. This platform carries a contact 26 which is connected by a wire 27 to one side of the magnet 22. The opposite side of this magnet is connected by a wire 28 to a wire 29 which wire is in turn connected to a battery 31, the opposite side of this battery is connected to a wire 32, to a wire 33 which wire 33 connects with a contact 34 positioned in the bottom of the receptacle 14, the result being that when a weight such as a robber being deposited into the receptacle 14 comes to bear upon the platform 23, the contacts 26 and 34 will engage each other. 90 This will immediately cause electric current to flow from the battery 31 through the wire connections to the magnet 22 which will actuate the latch 21 and will cause the cover 16 to fall to the dotted line position of Figure 1, thus locking the robber within the receptacle.

By now lifting the ring 19, the entire receptacle together with the robber deposited therein may be removed and transported to 100 any desired place.

In order to actuate the latch 11, I provide a contact 36 located on the surface of the counter 37, the wiring of this contact 36 is such that it will operate the latches 11 when 105 pressed. The teller by raising his knee may operate this contact without the robber being aware of the fact that he is doing so. At the same time the contact 36 is also adapted, through suitable wiring, to actuate latch 39. These latches serve to maintain a shield 41 which travels in track 42 at a po-

sition above the top line of the windows 7 and 8. Immediately upon the actuation of the latches 39 this shield 41 will descend, thus further protecting the employee 5 against bodily harm by the robber.

It will thus be seen that by employing my device it is possible for a bank employee to deposit the robber within a closed receptacle and at the same time to drop a shield 10 in front of the window thereby protecting himself.

It is to be understood that the form of my invention herewith shown and described is to be taken as a preferred example of the 15 same and that various changes relative to the material, size, shape and arrangement of parts may be resorted to without departing from the spirit of the invention or the scope of the subjoined claims.

20 Having thus described my invention, I claim:—

1. In a robber trap, a floor having a trap door positioned therein, a funnel shaped member secured to said floor, and surround-

ing said trap door, a downwardly extending pipe secured to said funnel shaped member, a receptacle positioned beneath said pipe, a vertically movable ring serving to connect said pipe and said receptacle and a hinged 30 cover secured to said receptacle and adapted to be automatically closed after a body has been deposited within said receptacle.

2. In a robber trap, a floor having a trap door positioned therein, a funnel shaped member secured to said floor, and surrounding said trap door, a downwardly extending pipe secured to said funnel shaped member, a receptacle positioned beneath said pipe, a vertically movable ring serving to connect 35 said pipe and said receptacle and a hinged 40 cover secured to said receptacle, a latch for normally maintaining said cover in open position, a movable platform within said receptacle and means carried by said platform for actuating said latch when said 45 platform is depressed.

In testimony whereof I affix my signature.
EZEKIEL M. ROCHA.
